(57) CLAIM

The ornamental design for a packaging as shown and described.

DESCRIPTION

The file of this patent contains at least one drawing/photograph executed in color. Copies of this patent with color drawing(s)/photograph(s) will be provided by the Office upon request and payment of the necessary fee.

The sole FIGURE is a front plan view of the packaging in a flat unwrapped state showing our new design.

The broken lines shown in the drawings are for the purpose of illustrating parts of the article that form no part of the claimed design.

1 Claim, 1 Drawing Sheet
